UNITED STATES PATENT OFFICE.

JOHN J. KAUFFMAN, OF MONOCACY STATION, PENNSYLVANIA.

DRAWING DIE.

Application filed March 27, 1924. Serial No. 702,203.

To all whom it may concern:

Be it known that I, JOHN J. KAUFFMAN, a citizen of the United States, residing at Monocacy Station, in the county of Berks 5 and State of Pennsylvania, have invented certain new and useful Improvements in Drawing Dies, of which the following is a specification.

This invention relates to improvements 10 in drawing dies, and the object in the present instance is to provide a die in which, by a single operation, a completed article may be made, where it has heretofore required a plurality of operations, as for instance a 15 relatively deep cup like metal piece.

The invention consists of a duplex die provided with a series of radially arranged plungers adapted to move in unison with each other and synchronically with the 20 movement of the cutting and drawing members of the die, and these plungers are so placed and connected that each will supply a proportional share of the effort required to properly draw the object to form.

25 The object of the invention being primarily to finish the product at a single operation without danger of the die tearing through the article being drawn.

The invention is more fully described in 30 the accompanying specification and clearly illustrated in the drawings forming a part of this application, and in which:

Figure 1 is a central sectional view of my invention, with the disc cut from the sheet 35 stock and the drawing die ready to begin its downward movement.

Figure 2 is a like view, with the die approaching the limit of its downward movement.

40 Figure 3 shows, in part, a plan view with the die removed—in part a section through 3—3—and in part a section through 4—4, of Figure 1.

Figure 4 is an enlarged fragment in perspective, showing the juncture between a 45 rock arm and a plunger.

The numeral 1 designates the die holder. 2 represents the male and 3 the female member of the cutting die. 4 represents the 50 male and 5 the female member of the drawing die.

The numeral 6 designates the ejector, which is formed with a cone-shaped base member 7 and which latter is backed by a 55 spring 20 adapted to return the ejector to

normal raised position and incidently to open the plungers 8.

These plungers 8 are arranged radially in the die holder, and the number will be determined by the particular work to be done by the dies in any given case. These plungers are each carried on the upper extremity of a rock arm 9, which latter are pivotally mounted in the die holder, below the plungers and the connection between each rock arm and plunger is through the medium of a pin 12 carried by the plunger and fitting slidably in an elongated slot 13 in the jaw-shaped upper extremity of the rock arm. 70

The lower extremities of these rock arms are each provided with a roller 10, and these rollers rest normally against the tapered wall of the cone-shaped member 7. The member 7 is formed with a flanged lower 75 extremity to serve as a resistance for the spring located beneath it and which tends to keep it normally raised.

As indicated in Figure 3, the plungers and the rockarms are arranged radially in 80 the die holder, each adapted to move freely in its respective slot.

The numeral 15 designates a sheet of metal or other stock from which the object, in the form of a blank is to be cut. The cutting die 2—3 cuts the blank, designated in Figure 1 by the numeral 16 and holds it firmly against the upper face of the female member 6 of the drawing die, and the male member of the drawing die begins its downward movement, depressing the centre of the disc and with it the ejector 6, against the compression of the spring 20. 85 90

As this downward movement of the drawing die continues, the tapered or cone-shaped member 7 will bear against the rollers 10 and cause the rockarms 9 to turn on their pivotal points, which will move the upper extremities of the rockarms inwardly, toward the centre of the die holder. Inasmuch as each rockarm carries one of the plungers on its upper end, this movement will cause all of the plungers to move toward the centre in unison. The inner ends of these plungers extend normally to the line of the inner wall of the die member 3, so that, when the blank 16 has been formed, as above described, by the descent of the die member 2, the inner ends of these plungers bear a very intimate relation with the 105 110

periphery of the said disc blank, and as soon as the downward movement of the member 7 begins, and the rockarms move, these plungers will begin to exert a pressure against the edge of the blank 16, so that the formation of the product is very materially aided in that pressure is brought to bear against this blank from all points, helping to force the metal into the die as 10 the plunger forces it downward, with the result that the metal disc is drawn into the desired shape without any undue strain or pressure being exerted at one point. The drawing of the metal has been accomplished 15 by the drawing die proper, but it has been relieved of a great portion of its duty by the aid of the series of radially arranged and coacting plungers, which have forced the metal into proper position gradually as the 20 die has been lowered, thus effecting a complete product in a single operation.

The spring 20 in its opening action, returns the ejector to its normal position within the drawing die, and, in its upward 25 movement, it ejects the finished article, made by the downward action of the die member 2, above described.

What I claim and desire to secure by Letters Patent, is:

30 1. A drawing die comprising a die holder, a cutting die, a drawing die, a series of radially movable plungers, a series of rockarms

connected with the plungers and pivotally mounted in the die holder, rollers carried by the rockarms, an ejector having a tapered portion against which the rollers bear, and means for actuating said rockarms and plungers in unison and synchronically with the drawing die. 35

2. In a drawing die, a die holder, a cutting die, a drawing die, a series of radially arranged plungers, a series of radially arranged rockarms to which the plungers are attached, an ejector movable in the drawing die, said ejector having a tapered wall 45 adapted to actuate the rockarms and the plungers in unison with each other, and spring means for returning the ejector to normal raised position. 40

3. In a device of the character described, a die holder, a cutting die, a drawing die, a series of radially movable plungers in the die holder, a series of pivotally mounted rockarms for actuating the plungers, a vertically movable ejector actuated in one direction by the drawing die, rollers carried by the rockarms and adapted for contact by the ejector, whereby the actuation of the drawing die will cause the rockarms and the plungers to move in unison with each other and synchronically with the drawing die. 50 55

In testimony whereof I affix my signature. 60

JOHN J. KAUFFMAN.
